Primary Examiner — Richard Edgar*Assistant Examiner* — Jessica Ruth Grable(74) *Attorney, Agent, or Firm* — Egbert, McDaniel & Swartz, PLLC(57) **CLAIM**

The ornamental design for a pair of armrests as shown and described.

DESCRIPTION

FIG. 1 is a front, upper and right side perspective view of a pair of armrests showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, lower and right side perspective view thereof;

FIG. 9 is a front, upper and right side perspective view, wherein the pair of armrests are in a folded state; and, FIG. 10 is an isolated perspective of the right side armrest, an isolated perspective view of the left side armrest being a mirror image thereof.

The broken lines of FIGS. 1-9 illustrate environmental matter and form no part of the claimed design.
